UNITED STATES PATENT OFFICE.

CHARLES HOFMANN, OF CHICAGO, ILLINOIS.

DESIGN FOR A CLOCK-FRAME.

SPECIFICATION forming part of Design No. 25,077, dated January 21, 1896.

Application filed December 20, 1895. Serial No. 572,796. Term of patent 3 $\frac{1}{2}$ years.

To all whom it may concern:

Be it known that I, CHARLES HOFMANN, a citizen of the United States, residing at Chicago, Cook county, Illinois, have invented and produced a new and original Design for Clock-Frames, reference being had to the accompanying drawing, forming a part hereof.

In the accompanying drawing the figure is a front elevation of my design for a clock-frame.

The leading feature of my design consists in a casing or frame for a clock, comprising a representation of a draped human figure standing on a base, with one arm resting on the portion adapted to hold the movement and the other hand resting on a column.

A is the representation of a draped human figure standing on the base B, C the portion for the movement with one hand of the figure resting thereby, and D the column with the other hand of the figure resting thereby, the whole presenting to the eye a harmonious and ornate figure, as illustrated in the drawing.

I claim—

The design for a clock frame herein shown and described.

CHARLES HOFMANN.
